UNITED STATES PATENT OFFICE.

WELLINGTON PARKER KIDDER, OF BOSTON, MASSACHUSETTS, ASSIGNOR, BY MESNE ASSIGNMENTS, TO THE NOISELESS TYPEWRITER COMPANY, OF MIDDLEBURY, CONNECTICUT, A CORPORATION OF CONNECTICUT.

TYPE-WRITING MACHINE.

1,121,018.

Specification of Letters Patent. Patented Dec. 15, 1914.

Application filed April 25, 1906. Serial No. 313,528.

To all whom it may concern:

Be it known that I, WELLINGTON PARKER KIDDER, residing at Boston, in the county of Suffolk and State of Massachusetts, have invented certain new and useful Improvements in Type-Writing Machines, of which the following is a full, clear, and exact description, such as will enable others skilled in the art to which it appertains to make and use the same.

This invention relates to typewriting machines, and has special reference to the line-spacing mechanism.

The principal object in contemplation is to embody in a typewriting machine, mechanism of the above character which shall be positive and reliable in action, easy of adjustment and, at the same time, of such construction as will enable it to be operated without the production of noise, thereby adapting the same especially for use in noiselessly operating typewriters.

Other objects will be in part obvious and in part pointed out hereinafter.

The invention accordingly consists in the features of construction, combinations of elements, and arrangement of parts, which will be exemplified in the mechanism herein-after described, and the scope of the application of which will be indicated in the appended claims.

In the accompanying drawings, wherein is illustrated one of the various possible embodiments of my invention, Figure 1 is a view in elevation, showing a portion of a typewriting machine embodying the same. Fig. 2 is a similar view, but showing the operative mechanism in a different position. Fig. 3 is a vertical sectional view taken on line *a—a*, Fig. 1, certain of the parts being shown in elevation.

Similar reference characters refer to similar parts throughout the several figures of the drawing.

In typewriting machines as heretofore constructed, considerable noise has been produced by the clicking of the pawl and ratchet mechanism employed to effect the line-spacing movement of the platen, but by my invention, which I shall presently describe in detail, I have provided a construction whereby all noise in operation is avoided. I secure this noiseless operation

by so mounting the actuator or feed-pawl that the same will be normally held out of engagement with the ratchet-wheel on the platen, but will be automatically thrown into engagement therewith on the upward or working thrust of the pawl, and automatically disengaged therefrom on the beginning of the downward or return stroke, so as to ride free of such ratchet. I have, moreover, obtained the above and other desired ends through the provision of exceedingly simple mechanism, as will be apparent hereinafter.

Referring now to the drawings, wherein I have shown a portion of a typewriting machine sufficient to illustrate the structural features of my invention and the novel principles involved therein, 1 denotes a portion of the platen frame or carriage having at either end thereof uprights 2, but one of which is shown, as in the drawings there is illustrated only that portion of the platen-frame whereon my invention is employed. It will be understood, of course, that the opposite end of the platen frame is provided with an upright similar to that shown in the drawing. Journaled in uprights 2 and 80 extending therebetween is a shaft 3 upon which is mounted the paper-roll or platen 4, securely positioned thereon and adapted to rotate with said shaft to feed the paper for line-spacing. Platen-shaft 3 extends at either end outwardly from uprights 2 and has fixed thereon the usual small hand-wheels or knobs, one of which is shown at 5, serving to turn the platen in its bearing for universal spacing.

The platen is adapted, through shaft 3, to be rotated for line-spacing through the instrumentality of a spacing element positioned upon said shaft, such spacing element being in the present instance comprised by a crown ratchet-wheel 6, the teeth of which extend inwardly toward the end of the platen and have their working shoulders faced downwardly as clearly shown in Fig. 2.

Upon a lateral extension or bracket 7 of platen-frame 1 is pivoted as at 8 one leg 9 of a line-spacing lever 10, provided with a hand-engaging portion 11, and carrying upon another leg 9' as at 12, by means of pivot 13, an actuator or feed-pawl 14, said

feed-pawl being loosely mounted upon its pivot for a purpose which will be presently explained. Bracket 7 has mounted thereon an upwardly extending plate 15, provided on its exposed face with a friction surface 5 against which bears a lateral projection or tail piece 16 extending from the feed-pawl. Upright 2 of the platen-carriage is in the present instance, provided with a laterally extending lug 17 which is shown as being integral therewith and which is cam-faced as at 18. This projection or lug constitutes a fixed stop to limit the upward or feeding thrust of the actuating pawl, which is 10 turned at its upper end at 14' to coöperate with the cam surface of said stop.

In order that variable line-spacing movements of the platen may be effected, a movable stop-device is arranged beneath the 20 actuator or feed-pawl. This stop-device is comprised by a detent 19 having a plurality of stepped abutments or shoulders 20 and is journaled upon a stud-screw 21 threaded into the end wall of the platen-carriage.

25 Detent 19 is capable of adjustment upon stud-screw 21 by means of knurled handle or knob 22 to carry any one of the shoulders in the path of tail piece 16 of the feed-pawl 14, so as to intercept or arrest said pawl as it oscillates to its normal or initial position, the detent being held in its several adjusted positions by a pin 23 engaging with any one of series of slight depressions 24 arranged on the end wall of the platen-carriage. Spacing-lever 10 is provided with a returning spring 25 to normally hold the same in such position that the tail piece of feed-pawl 14 is engaged with one of the several stepped shoulders of detent 19; and 30 feed-pawl 14 is provided with a lug 26 engaging with the end wall of the platen-frame, such engagement limiting its pivotal movement from the ratchet-wheel and holding the same in the position shown in 35 Fig. 1.

Having thus described the structural features comprising this adaptation of my invention, the operation thereof may now be understood.

50 With the parts in the position as shown in Fig. 1, a pull on the spacing-lever 10, as when it is desired to return the carriage to initial position to commence a new line, will first swing said lever upon its pivot and by 55 means of leg 9' will lift feed-pawl 14, which is loosely pivoted thereon, as above explained. During this movement of the feed-pawl tail piece 16, arranged to one side thereof, by its frictional engagement or drag 60 along plate 15, tends to retard that portion, which retardation swings said pawl upon its pivot and in the continued upward movement thereof forces the same into engagement with one of the teeth of crown ratchet- 65 wheel 6; and thereafter said ratchet-wheel

will be forced to rotation by said feed-pawl and the platen rotated one or more line spaces thereby, such feeding movement being arrested by the engagement of said feed-pawl with fixed stop 17. It will be noted 70 that the engagement of feed-pawl 14 with its limiting stop will through the connected parts prevent a further pivotal movement of the spacing-lever, whereby a continued pull on said lever will carry the carriage to 75 its initial or line-commencing position. Upon the release of pressure from spacing-lever 10, said lever will, under the influence of spring 25, be returned to normal position, but, on the beginning of the downward or return stroke, the drag produced upon plate 15 by the frictional contact therewith of tail piece 16 of feed-pawl 14 will swing said pawl out of engagement with ratchet-wheel 6, so that the same will 80 ride clear of said ratchet-wheel during its movement to initial position. The adjustment of detent 19 determines the extent of movement of feed-pawl 14 on its return stroke and arrests the same by means of one 85 of the stepped shoulders 20 in any one of several predetermined positions. The adjustment of detent 19, moreover, determines the point of initial engagement of said feed-pawl 14 with ratchet-wheel 6 and thus 90 regulates the rotative movement of the platen for line-spacing whereby pre-determined movements of the platen for one or more line spaces may be effected as desired. It will accordingly be apparent that I have 95 provided mechanism characterized by simplicity and efficiency for attaining the objects of my invention. As the feed-pawl is normally disengaged from the ratchet-wheel and is in engagement therewith only when 100 the platen is being rotated for line-spacing, such operation may be accomplished with the production of little noise, since the feed-pawl is not allowed to drag or click over the teeth of the ratchet-wheel, but is swung 105 by means of the friction drag from its engagement therewith, so as to ride free therefrom while returning to initial position. As 110 will be apparent the friction may be applied to the feed-pawl in other ways than that herein shown, it only being necessary to create a friction or drag upon one side of the pivot, whereby the working end of such pawl will be engaged with the ratchet. Also, as will be obvious, the mechanism 115 above-described may be used with great facility in other relations, although it is particularly valuable and useful in the relation herein shown.

As many changes could be made in the 120 above construction and many apparently widely different embodiments of my invention could be made without departing from the scope thereof, I intend that all matter contained in the above description or shown 125

in the accompanying drawing shall be interpreted as illustrative and not in a limiting sense.

Having described my invention, what I claim as new and desire to secure by Letters Patent is:—

1. In a typewriting machine, the combination with the platen and its ratchet-wheel, of a line-spacing lever, an actuator carried by said line-spacing lever, and a friction device with which a portion of said actuator engages, whereby the same is swung into engagement with the teeth of said ratchet-wheel when said line-spacing lever is operated for line-spacing, said device being also adapted by its frictional engagement with said portion of the actuator to swing the same from the teeth of said ratchet-wheel during the returning movement of said line-spacing lever to initial position.

2. In a typewriting machine, the combination with the platen and a ratchet-wheel carried thereby, of a line-spacing lever having an actuating movement in the direction of the axis of the platen, an actuator having a pivotal connection with said line-spacing lever, frictional means associated with said actuator whereby said actuator is adapted to be moved into engagement with said ratchet-wheel during movement of said line-spacing lever for line-spacing and being also adapted to ride free therefrom during the return movement of said line-spacing lever.

3. In a typewriting machine, the combination with the platen and its ratchet, of a line-spacing lever, an actuator loosely pivoted upon said line-spacing lever, and means free from said actuator but frictionally contacting therewith to swing the same into engagement with said ratchet when said line-spacing lever is operated for line-spacing, and to swing said actuator clear of the ratchet during the returning of said line-spacing lever to initial position.

4. In a typewriting machine, the combination with the platen and its ratchet, of a line-spacing lever, an actuator having a loose pivotal connection thereon, and frictional means for automatically swinging said actuator toward and from said ratchet during the line-spacing and returning movements, respectively, of said line-spacing lever.

5. In a typewriting machine, the combination with the platen and its ratchet-wheel, of a line-spacing lever, an actuator having a loose pivotal connection thereon, and a stationary friction device with which a portion of said actuator engages, whereby the same is swung to engage the teeth of said ratchet-wheel during movement of said line-spacing lever for line-spacing, said device being also adapted to swing said actuator to clear the ratchet during the returning movement of said line-spacing lever.

6. In a typewriting machine, the combination with the platen frame and platen, of a ratchet-wheel on the platen, a line-spacing lever pivotally mounted upon the platen frame, an actuator loosely pivoted upon said line-spacing lever, and means arranged intermediate the pivotal support of said line-spacing lever and that of said actuator adapted frictionally to engage said actuator and move the same into engagement with said ratchet-wheel when the line-spacing lever is operated for line-spacing.

7. In a typewriting machine, the combination with the platen-carriage and platen, of a ratchet carried by the platen, a line-spacing lever pivoted upon a bracket extended from the platen-carriage, a feeding-pawl pivoted upon the line-spacing lever, and a friction plate engaging a portion of said feeding-pawl to move said pawl into engagement with said ratchet when the said line-spacing lever is moved in its line-spacing direction and to disengage the same from said ratchet during the returning of said line-spacing lever to initial position.

8. In a typewriting machine, the combination with the platen-carriage and a platen, of a ratchet carried by the platen, a feeding-pawl for the ratchet, a line-spacing lever having one of its legs pivoted upon the platen-carriage and upon the other leg of which said feeding-pawl is pivoted, and a plate arranged intermediate the pivotal support of said line-spacing lever and that of said pawl frictionally to swing said feeding-pawl into engagement with said ratchet when the line-spacing lever is operated for line-spacing and out of engagement therewith when said ratchet is returning to initial position.

9. In a typewriting machine, the combination with a platen-carriage and a platen carried thereby, of a ratchet carried by the platen, a line spacing lever having an actuating movement in the direction of the axis of the platen, an actuator pivotally mounted directly on said lever, and a friction device mounted on the platen carriage in frictional engagement with said actuator to swing the actuator into and out of engagement with the ratchet during the swinging movement of the line spacing lever.

10. In a typewriting machine, the combination with the platen and its ratchet, of a line-spacing lever having an actuating movement in the direction of the axis of the platen, a feeding-pawl pivotally mounted thereon, and a movable stepped-stop, which, by its engagement with said pawl, determines the point of initial engagement thereof with said ratchet, and a fixed stop for limiting the feeding-thrust of said pawl.

11. In a typewriting machine, in combination, a frame, a platen, a ratchet associated therewith, a line-spacing lever, and a

frictionally actuated pawl mounted on said lever in frictional contact with a portion of the frame adapted to be moved into engagement with said ratchet when said line-spacing lever is actuated and to be withdrawn from engagement with said ratchet upon the return movement of said line-spacing lever.

12. In a typewriting machine, a platen, a ratchet associated therewith, a line-spacing lever, an actuator for the ratchet normally out of engagement therewith, and means frictionally engaging said actuator adapted to swing the same into engagement with said ratchet when said line-spacing lever is operated for line-spacing.

13. In a typewriting machine, the combination with the platen and its ratchet-wheel, of an actuator for said ratchet wheel a line-spacing lever upon which said actuator is pivotally supported, having an actuating movement in the direction of the axis of the platen, a shiftable stop device provided with a plurality of stop elements, each of which is adapted to determine the point of engagement of said actuator with said ratchet-wheel, and a fixed stop element for limiting the thrust of said actuator.

14. A line-spacing mechanism for typewriters comprising a platen-carriage, a ratchet-wheel, a line-spacing lever, a pivotally mounted actuator carried thereby, a variable stop device disposed for presentation to the actuator to normally hold the same out of engagement with said ratchet-wheel, a fixed stop for limiting the thrust of said actuator, and a device for frictionally engaging said actuator to carry the same into and out of engagement with said ratchet-wheel during the feeding and returning, respectively, of said line-spacing lever.

15. A line-spacing mechanism for typewriting machines comprising a platen and its ratchet-wheel, an actuator for the ratchet-wheel, a line-spacing lever upon which said actuator is pivoted, a variable stop device for determining the normal position of said actuator with respect to said ratchet-wheel, said device also operating normally to hold the same out of engagement therewith, a fixed stop for limiting the thrust of said actuator while in engagement with said ratchet-wheel, and a friction device engaging said actuator at one side of its pivotal support whereby the same is engaged with said ratchet-wheel during the movement of said line-spacing lever for line-spacing and is disengaged from said ratchet-wheel during the returning of said line-spacing lever to initial position.

16. In a typewriting machine, in combi-

nation with the platen-carriage, a shaft journaled therein, a platen carried by said shaft, a ratchet-wheel also carried by said shaft, a line-spacing lever pivoted upon a bracket extending from said platen-carriage, a feeding-pawl provided with a tail piece pivotally mounted upon said line-spacing lever, said feeding-pawl being normally out of engagement with said ratchet-wheel, a plate having a friction surface engaging the tail piece of said actuator and adapted to carry said actuator into engagement with said ratchet-wheel when said line-spacing lever is operated for line-spacing, said plate being also adapted to disengage said feeding-pawl from said ratchet-wheel during the returning movement of said line-spacing lever toward normal position, a fixed stop for limiting the feeding thrust of said pawl, and a stop device carried by the platen-carriage and provided with a plurality of shoulders, each of which is adapted to be interposed in the path of the tail piece of said pawl whereby said pawl may be normally maintained in a plurality of predetermined positions with respect to said ratchet-wheel.

17. In a typewriting machine, the combination with a platen and a ratchet associated therewith for line spacing the same, of a line spacing lever, a pawl actuated thereby, and a stationary plate in contact with said pawl in all positions whereby said pawl is moved into engagement with said ratchet when the line spacing lever is actuated.

18. In a typewriting machine, the combination, with a platen and a ratchet operatively associated therewith, of a line spacing lever, a pawl pivotally mounted on said lever, and a stationary plate in frictional contact with said pawl at all times whereby it is frictionally actuated and swung about its pivot on said line-spacing lever when said lever is actuated to carry the pawl into engagement with said ratchet.

19. In a typewriting machine, in combination, a frame, a platen thereon, a ratchet at one end of said platen, a line-spacing lever, and a frictionally actuated pawl movable relatively thereto in a plane parallel to and closely adjacent the plane of movement of said lever as it is actuated, whereby said pawl is carried into and out of engagement with said ratchet as said lever oscillates.

In testimony whereof I affix my signature, in the presence of two witnesses.

WELLINGTON PARKER KIDDER.
